UNITED STATES PATENT OFFICE.

JOHN HENRY KELLER, OF NEW ORLEANS, LOUISIANA.

DESIGN FOR A CAKE OF SOAP.

SPECIFICATION forming part of Design No. 14,607, dated February 5, 1884.

Application filed December 10, 1883. Term of patent 14 years.

To all whom it may concern:

Be it known that I, JOHN H. KELLER, of New Orleans, in the parish of Orleans and State of Louisiana, have invented and produced a new and original Design for a Cake of Soap, of which the following is a full, clear, and exact description.

My design, which is for soap in a cake form, adapted for both toilet and laundry use, has for its leading feature or general configuration the representation of a bale of cotton; and it consists in an ornamentation of one or more of its sides by parallel transverse grooves or creases representing the hoops which bind or hold the bale together, and in an ornamentation of one of its sides, having parallel transverse grooves or creases representing the hoops which bind the bale, with square or rectangular projections representing fastenings by which the hoops on the bale are secured.

Reference is to be had to the accompanying drawings, forming part of this specification, and in which the figure represents a perspective view of a cake of soap illustrating my design.

A is a cake of soap of parallelogrammic form,

in its general configuration representing a bale of cotton. Each or any or all of its sides are ornamented by a series of parallel transverse grooves or creases, *b b*, representing the hoops by which the bale is bound together, and the one of these grooved or creased sides is further ornamented midway of each of its creases with a square or rectangular projection, *c*, representing fastenings by which the hoops on the bale are secured.

I claim—

The design for a cake of soap herein shown and described, the same showing a body or figure of rectangular form representing a bale of cotton, and parallel transverse grooves or creases in one or more of its sides, representing hoops used to bind or hold the bale together, and further ornamented with projections intermediately of the length of the creases on one of its sides, representing fastenings by which the hoops on the bale are secured.

JOHN HENRY KELLER.
